UNITED STATES PATENT OFFICE.

MARQUIS F. SEELEY, OF CHICAGO, ILLINOIS.

GRAIN DUMP AND ELEVATOR.

SPECIFICATION forming part of Letters Patent No. 410,336, dated September 3, 1889.

Application filed May 7, 1888. Serial No. 273,024. (No model.)

To all whom it may concern:

Be it known that I, MARQUIS F. SEELEY, of Chicago, in the county of Cook and State of Illinois, have invented certain new and useful Improvements in Grain Dumps and Elevators; and I do hereby declare that the following is a full, clear, and exact description thereof, reference being had to the accompanying drawings, and to the letters of reference marked thereon, which form a part of this specification.

This invention relates to an improved grain dump and elevator adapted for use in places at which the amount of work to be done will not warrant the use of a steam-engine or other costly power plant for driving the elevator.

The invention consists in the matters hereinafter described, and pointed out in the appended claims.

In the accompanying drawings, illustrating the invention, Figure 1 is a plan view of an apparatus embodying the main features of my invention, part being shown in section and part broken away. Fig. 2 is a cross-sectional view of the same, taken upon line 2 2 of Fig. 1. Fig. 3 is a longitudinal vertical section of the same, taken upon line 3 3 of Fig. 1. Fig. 4 is a cross-section taken upon line 4 4 of Fig. 3. Fig. 5 is a cross-section taken upon line 5 5 of Fig. 3. Fig. 6 is a detail sectional elevation taken upon line 6 6 of Fig. 5. Fig. 7 is a plan view of a tread-power differing somewhat from that shown in Fig. 3. Fig. 8 is a vertical section of the same, taken upon line 8 8 of Fig. 7. Fig. 9 is a detail section of the same, taken upon line 9 9 of Fig. 8. Fig. 10 is a plan view of an elevating device and dump containing two tread-powers. Fig. 11 is a detail section taken upon line 11 11 of Fig. 10. Fig. 12 is a plan view, partly broken away, of a dump and elevating apparatus combined with means for delivering grain or ear-corn thereto from an adjacent bin or crib. Fig. 13 is a vertical section of the same, taken upon line 13 13 of Fig. 12. Fig. 14 is a vertical section taken upon line 14 14 of Fig. 12. Fig. 15 is a sectional view of the dump-platform, taken upon line 13 13 of Fig. 12, illustrating another construction in a horizontal conveyer. Fig. 16 is a horizontal vertical section of a dump-platform, illustrating a modified construction in the tread-power and a

novel construction in movable guards for confining the horses upon the tread-power. Fig. 17 is a cross-section of the same, taken upon line 17 17 of Fig. 16. Fig. 18 is a fragmentary plan view of one side of the tread-power and adjacent parts shown in Figs. 16 and 17. Fig. 19 is a side elevation of my invention.

As illustrated in said drawings, A indicates as a whole a dump-platform consisting of a horizontal flooring A', which is elevated above the ground commonly about four or five feet, and inclined driveways A² A³ to allow the passage of a horse and wagon to and from the top of the platform. The said platform is herein shown as self-contained or separate from any other structure, so that it is in a measure portable and may be moved from place to place. The platform may, however, be permanently erected or may form part of a storage or other building.

B are two dump-timbers arranged in slots in the floor A' of the platform and sustained upon pivots b b in such manner that a wagon supported thereon may be tipped or tilted by the swinging of the dump-timbers, as heretofore common in wagon-dumps.

b' b' are guide-strips upon the dump-timbers and b² b² curved guides upon the platform to direct the wagon-wheels to proper position upon the timbers, as common in wagon-dumps as heretofore made.

C is a hopper located beneath an opening a in the floor A' at the rear of the dump-timbers. The said opening a is provided with a door A⁴, which is closed when the horses are passing over the opening, and is opened to allow the grain discharged from the wagon to enter the hopper. The walls of said hopper C slope laterally, and said hopper discharges into an elevator-boot D, through which passes an elevator-belt E, by which the grain passing from the hopper to the boot is elevated and discharged into a spout F, by means of which it may be delivered at a desired point.

As herein illustrated, the elevator-belt E is a chain belt carrying a series of buckets, the belt being carried over a sprocket-wheel E' in the boot D and over two elevated pulleys E² E³, arranged to bring the belt into such position that the buckets will discharge freely into the spout F. Said spout may be carried

to any suitable point of discharge, but as herein illustrated is arranged to deliver into a box F', provided with a turn-spout F² in its bottom, whereby the grain may be delivered 5 as desired to any one of a number of places or bins. The sprocket-wheel E' in the boot D is mounted upon a horizontal shaft D', which passes through the side of the boot and beneath the dump-platform and has 10 suitable bearings upon the same. Said shaft D' is provided with a sprocket-wheel D², by means of which the shaft is driven.

G is a tread-power, adapted for actuation by a horse or horses and located in-or upon 15 the platform A' at a point in advance of the dump-timbers B B, and in such position that when a wagon is resting upon the dump-timbers the horses attached thereto will stand upon the tread-power. The said tread-power, 20 as shown in Figs. 1 to 6, consists of two shafts G' G², provided with sprocket-wheels g g', over which is placed the belt G³, composed of slats attached to chains, as heretofore common and well known. The shaft G' is extended 25 past the bearings a² a², which are attached to longitudinal beams a' a' of the frame at either side of the belt G³, and is provided with additional bearings a³ a³ at its ends, herein shown as attached to the side walls of 30 the dump-platform. Upon the said shaft G' is secured a sprocket-wheel G⁴, over which passes a chain belt G⁵, by means of which motion is communicated to the sprocket-wheel D² upon the elevator-shaft D', over which 35 sprocket-wheel the said chain belt also passes.

For holding the tread-power from movement at the time the horses are drawing the wagon forward to its place upon the dump-timbers, and for starting and stopping it at desired 40 times, any suitable locking or holding device may be employed. As shown in the drawings, a friction-brake is for this purpose applied to a pulley H² upon the shaft G', such brake having the advantage of enabling the operator 45 to control the movements and speed of the tread-power in starting and stopping it, and at other times, as well as to hold the same immovable when necessary.

As shown in the drawings, Figs. 3, 5, and 6, 50 H is the hand-lever of the friction-brake, which hand-lever is mounted upon the platform and is attached to one end of a brake-strap H', the opposite end of which is secured to a stationary support and which passes 55 around a pulley H², secured to the shaft G'. By moving the hand-lever the strap may be tightened or loosened and the rotation of the shaft either entirely stopped or checked, as desired. The stopping or checking device is 60 of special advantage in cases where nervous or inexperienced horses are employed to operate the machine, the operator being able by its use to control the movements of the belt while the horses are becoming accustomed 65 to its movement—as, for instance, by allowing it to move slowly at first.

In the device shown in Figs. 1 to 6 the

tread-power belt is arranged horizontally, so that the power is obtained solely by the pulling of the horses against the traces which 70 are attached to the wagon, which latter will be secured so as to prevent any movement thereof during the operation of the tread-power. The latter may, however, be inclined in such manner that the power is exerted by 75 the weight of the horse, in a manner herein shown and hereinafter set forth. The operation of the apparatus is as follows: The wagon laden with grain which is to be deposited in a bin, crib, or other receptacle, is drawn 80 by the horses into position upon the dump-timbers B B and the latter and the wagon are tipped to discharge the grain into the hopper C. As soon as the grain begins to run into said hopper, the tread-power is started and the 85 grain running into the elevator-boot from the hopper is elevated as it runs into the boot, the discharge of the grain from the wagon usually being regulated or controlled by a gate or otherwise, so that the grain is ele- 90 vated as fast as it is passed from the wagon into the hopper and boot.

In Figs. 7, 8, and 9 I have shown a construction in the tread-power wherein the latter is so arranged that it may be inclined 95 when in use. In this instance the tread-power comprises a slotted belt I, two shafts I' I', mounted in side bars I² I², which are pivotally supported upon the frame-timbers a' a' by means of pivots i i, Fig. 9, herein shown as 100 made of tubular form, said shafts being provided with sprocket-wheels I³ I³ for supporting the belt I. The side bars I² I² are rigidly connected with each other by means of cross-bars i' i', and the pivoted frame is held in and 105 shifted to a desired regular angular position by means of a pinion i², mounted in a standard i³ upon the platform and engaging a curved rack I⁴, attached to one of the side bars I². A third shaft I⁵ is mounted in 110 and extends through the tubular pivots i i, and is provided with sprocket-wheels I⁶, engaging chain belts forming part of the slotted belt of the tread-power. The shaft I⁵ is employed to transmit the motion of the tread- 115 power to the elevator, and may be provided with a sprocket-wheel for a drive-chain and friction-controlling device like those employed in connection with the shaft G'. (Shown in Figs. 1 to 6.) It may sometimes be found 120 desirable to employ for working the elevating apparatus a horse or horses other than those belonging to the wagon in which the grain is hauled to the elevator—as, for instance, the owner of the elevator may desire to employ 125 his own team to actuate the tread-power, instead of relying upon the horses belonging to the wagon for this purpose.

To provide an elevating device which may be operated in either of the ways above referred to, I employ the construction shown in Figs. 10 and 11. As shown in Fig. 10, J is a tread-power located at one side of the tread-power G in an extension A⁵ of the platform 130

A'. The tread-power J may be like the tread-power G in all particulars. Both tread-powers are adapted for connection with the elevator-driving shaft preferably by means of 5 a clutch mechanism allowing both or either of the tread-powers to be put in operative connection with the elevator, as desired. A convenient form of such clutch device is shown in Fig. 11. In said figure, G' is the driven 10 shaft of one tread-power and J' the shaft of the other tread-power. These shafts are arranged in alignment with each other.

K is a sprocket-wheel mounted upon the meeting ends of the shaft, and K' is a drive-chain passing over said sprocket-wheel and serving as a medium for the transmission of power to the elevator. The hub of said sprocket-wheel is provided at both ends with teeth or cogs, adapted to interlock with corresponding teeth or cogs upon sliding clutch-sleeves k k', mounted upon the shafts G' and J' at opposite sides of the sprocket-wheel. The said clutch-sleeves are actuated separately by means of hand-levers K² K³, connected with the sleeves in the usual manner. 25 By the use of said clutches either or both of the shafts G' J' may be coupled with the sprocket-wheel K in an obvious manner.

The clutch device is desirably so arranged 30 that both tread-powers may be placed in gear with the sprocket-wheel K in order that the horses belonging to the wagon may be utilized, in addition to other horses, in case greater power is required for driving the elevator than is afforded by a single pair of horses.

In Figs. 12, 13, and 14 I have shown an attachment to a dump and elevator adapted for delivering ear-corn or grain to the elevator-belt from a storage-bin or ear-corn crib. In this instance L is a corn or other grain crib or bin, at one side of which the elevator and dump is located, and which is provided with a hopper-bottom L' L', sloping to a transverse 40 trough or channel L², arranged at right angles to the sides of the dump-platform. L³ is a sliding cover for said trough. M is an endless-belt carrier, the upper part of which moves through the said trough L². Said endless-belt carrier consists of a chain belt M', provided with transverse conveyer-flights m m, which move through the trough L², carrying the grain thereon with them. The chain belt M' passes around a sprocket-wheel M², mounted upon the frame of the bin at the inner end of the trough L², and around a second sprocket-wheel M³, mounted upon the dump-platform over the inlet-opening of the elevator-boot D. The bottom of the trough 50 L² is cut away adjacent to the wheel M² to allow the upward passage into the trough of the chain belt and flights.

L⁴ is a detachable trough, forming an extension of the trough L² and reaching to a 60 point over the inlet-opening of the elevator-boot.

In the common use of the bin the slide L³

is allowed to remain in position to support the grain and prevent its entering the trough L². When, however, it is desired to deliver 70 to the elevator the grain within the bin, the slide is drawn out, allowing the grain to enter the trough. Motion being given to the belt-carrier in a direction to move the flights m m along the trough L² toward the elevator-boot, the grain will be carried by the said flights through the troughs L² and L⁴ and will fall into the boot, out of which it will be lifted by the elevating apparatus. 75

Actuating devices for the carrier M are 80 herein shown as provided, by means of a bevel-gear m', upon the shaft m² of the sprocket-wheel M³, which bevel-gear intermeshes with a gear N' upon a horizontal shaft N, mounted upon the dump-platform and provided with 85 a sprocket-wheel N², arranged to engage the chain belt G⁵, by means of which motion is transmitted to the elevator from the tread-power.

In cases where the bin is located at the 90 side of the dump-platform the carrier-belt M may be arranged as shown in Fig. 15. In this case a sprocket-wheel M⁴ is employed to sustain the end of the carrier-belt M nearest the elevator-boot, said sprocket-wheel being 95 located within the hopper C, which latter is provided with an opening C' for the passage of the carrier-belt. The said opening C' will of course be closed when the carrier-belt is taken out and the apparatus is in use for receiving grain from wagons. O is a trough, which in this case is located in position for the passage through it of the upper part of the carrier-belt, said trough forming a continuation of the trough L² in the same manner as does the trough L⁴. (Shown in Fig. 13.) 100 105

In Figs. 16, 17, and 18 I have illustrated a construction in a tread-power having some advantages over those illustrated in Figs. 3 and 8, together with a novel construction in 110 movable guards adapted to be placed at the sides of the tread-power to prevent the horses from moving sidewise from the same.

The tread-power shown in said Figs. 16, 17, and 18 is made as follows: P is the endless 115 belt or apron of the tread, said belt being supported upon sprocket-wheels P' P², which are mounted upon shafts P³ P⁴ at opposite ends of the tread-power. The shafts P³ P⁴ are mounted in side bars P⁵ P⁶, which are rigidly connected by cross-bars p p, and are pivotally supported at the forward ends upon the platform in such manner that the rear end of the apron may be swung down below the level of the platform. Said side pieces P⁵ 120 P⁶ may be pivotally supported in any suitable manner, as, for instance, by means of hollow sleeves, affording bearings for the shaft P⁴ in the manner illustrated in Fig. 9. When the shaft and sprocket-wheels at the 125 rear end only of the tread-power are dropped or lowered to give inclination to the working-surface of the apron or endless belt, motion is transmitted from the tread-power to the 130

elevator by means of a sprocket-wheel p' upon the shaft P^3 , over which sprocket-wheel p' is placed a chain belt p^2 , arranged in the same manner as the chain belt G^5 . (Shown in Figs. 1 to 5.) In some instances the chain belt thus arranged will be slightly slackened when the wheel p' is shifted up or down; but when the parts are arranged as illustrated the distance between the sprocket-wheels at opposite ends of said belt will remain practically the same when the tread-power is horizontal and inclined. When the tread-power is pivotally supported at one end in the manner last above described, I preferably counterbalance the same in order to enable it to be easily moved. I have shown in the drawings a counterbalance-weight Q , which consists of a receptacle filled with stones and supported upon arms $Q'Q'$, which are rigidly attached to side pieces P^5 of the horse-power. For raising and lowering the moving end of the tread-power in this instance I provide a gear-segment Q^2 , which engages with a pinion q , attached to a shaft Q^3 , which shaft is mounted upon a platform below the tread-power, so that the gear-segment Q^2 and adjacent parts may be entirely out of the way of horses or vehicles passing over the platform. To enable said shaft Q^3 to be conveniently operated, I have herein shown a shaft Q^4 , provided with a crank q' , as mounted upon a standard Q^5 , attached to the top of the platform in position convenient to be actuated by a person standing thereon, the shaft Q^4 being provided with a sprocket-wheel q^2 , over which passes an endless belt q^3 , which also passes over a sprocket-wheel q^4 upon the shaft Q^3 . Idlers $q^5 q^6$ serve to guide the belt q^3 vertically downward from the sprocket-wheel q^2 to points beneath the floor of the platform.

The guards for confining the horses in place upon the tread-power are constructed as follows: $R R$ are two vertically-arranged or slightly-inclined gates or guards consisting of a rectangular frame-work made up of frame pieces and flat strips or boards secured thereto in any desired manner. Said guards are connected at each end with rigid posts $R' R'$ upon the dump-platform by means of horizontally arranged links $r r$, pivotally connected at their opposite ends with said posts and with the guards, the pivots being so arranged that the guards may be swung back against the posts and parallel with the sides of the dump, so as to be entirely out of the way of a wagon passing over the tread-power, as indicated in dotted lines in said Fig. 18, or may be thrown forward adjacent to the side of the tread-power, as illustrated in full lines in said Fig. 18 and in Fig. 17. The links $r r$ are herein shown as connected by vertical pivots with the guards and with the posts $R' R'$; but the same general result may be obtained by links otherwise pivoted or arranged in case the links are adapted to sustain the guards in proper operative position and to allow the latter to be folded or thrust rearwardly or

backwardly away from the tread-power to allow the passage of wagons past or over the same.

In Fig. 19 I have shown a combined dump and elevating device constructed in accordance with my invention as employed in connection with a corn-sheller, grain-cleaner, or other similar machine. In said figure, A is the dump-platform provided with dump-timbers, a tread-power, and grain-hopper, in the manner hereinbefore described. E is the elevator-belt; F , the spout receiving the grain from the belt; F' , a grain-receptacle, and F^2 a turn-spout connected therewith. S is a corn-sheller, which is driven by means of a belt s on a pulley s' upon the upper pulley-shaft of the elevator. S' is the discharge-spout of the corn-sheller, which is arranged to discharge into a bin T . In the operation of the apparatus thus constructed a load of ear-corn from the wagon may be dumped into the hopper, elevated, passed through the corn-sheller, and delivered to the bin T . From the bin the shelled corn may be passed through a spout t to the same wagon from which the ear-corn was discharged; or the said bin T may be a storage-bin arranged to discharge into railway-cars upon a neighboring track or elsewhere. In other circumstances the discharge-spout S' of a corn-sheller arranged as described may discharge into a bin or receptacle such as is illustrated in Figs. 12, 13, and 14, in which case the devices shown in the figures last mentioned may be employed at any subsequent time to remove the grain from the bin and elevate it for the purpose of discharging the same into a wagon, railway-cars, or elsewhere.

The combined dump and elevator constructed and operated as herein set forth may be employed in other ways than in the particular ones mentioned to facilitate the handling of grain, as will readily suggest themselves in practice to the user of the apparatus.

I claim as my invention—

1. A dumping and elevating apparatus comprising a wagon-dump, a hopper located in position to receive material from a wagon upon the dump, an elevator adapted to receive material from the hopper, and a tread-power located in position to be operated by the horses attached to a wagon upon the dump and adapted to actuate the elevator, substantially as described.

2. A dumping and elevating apparatus comprising an elevated platform, a wagon-dump therein, a hopper located beneath the floor of the platform adjacent to the dump, an elevator adapted to receive material from the hopper, and a tread-power supported upon the platform and in position to be operated by the horses attached to a wagon upon the dump and adapted to actuate the elevator, substantially as described.

3. A dumping and elevating apparatus comprising a wagon-dump, a hopper located

- in position to receive material from a wagon upon the dump, an elevator adapted to receive material from the hopper, a tread-power for actuating the elevator located at a point 5 in front of and adjacent to the dump and in position to be operated by the horses attached to a wagon upon the dump, and a second or auxiliary tread-power also adapted to actuate the elevator, substantially as described.
- 10 4. The combination, with a dumping and elevating apparatus embracing a wagon-dump, a hopper, an elevator located in position to be operated by the horses attached to a wagon upon the dump, and a tread-power, of 15 a grain-bin having a conveyer extending from the lower part of the bin to the elevator, and operative connections between the tread-power and said conveyer, substantially as described.
- 20 5. The combination, with a platform and wagon-dump therein, of an elevator, a tread-power for actuating the same mounted in the platform in position to be operated by the horses attached to the wagon upon the 25 dump and having pivotal connection with the latter, and means attached to the tread-power for adjusting the latter and holding the same at a desired angle, substantially as described.
- 30 6. The combination, with a platform and wagon-dump therein, of an elevator, a tread-power for actuating the same pivotally supported at one end upon the platform in position to be operated by the horses attached to a 35 wagon upon the dump, and a counterbalance-weight attached to the frame of the tread-power, substantially as described.
7. The combination, with a wagon-dump and an elevator, of a tread-power located in position to be operated by the horses attached to a wagon upon the dump, and which tread-power is pivotally supported at its forward end and provided at its rear end with a shaft 40 provided with a sprocket-wheel, and a driving-belt trained over said wheel and the driving-pulley of the elevator, substantially 45 as described.
8. The combination, with an elevated platform, wagon-dump therein, an elevator, and a tread-power for actuating the same located upon the platform adjacent to the wagon-dump and in position to be operated by the horses attached to a wagon upon the dump, of movable guards located at the sides of the tread-power, substantially as described. 50
9. The combination, with an elevated platform, a wagon-dump therein, an elevator, and a tread-power for actuating the same located adjacent to the wagon-dump and in position to be operated by the horses attached to a wagon upon the dump, of guards located at the sides of the tread-power, stationary supports for said guards, and a plurality of pivoted links connecting the said guards with the said supports, substantially as described. 55
- In testimony that I claim the foregoing as my invention I affix my signature in presence of two witnesses.

MARQUIS F. SEELEY.
